UNITED STATES PATENT OFFICE.

ROBERT M. STEENE, OF DANBY, AND SAMUEL D. McFADDEN, OF BARSTOW, CALIFORNIA.

BURNER.

1,092,785.

Specification of Letters Patent.

Patented Apr. 7, 1914.

Application filed April 28, 1911. Serial No. 623,817.

To all whom it may concern:

Be it known that we, ROBERT M. STEENE and SAMUEL D. McFADDEN, citizens of the United States, residing, respectively, at 5 Danby, in the county of San Bernardino and State of California, and at Barstow, in the county of San Bernardino and State of California, have jointly invented new and useful Improvements in Burners, of which 10 the following is a specification.

This invention relates to burners, and more particularly to burners for utilizing liquid or gaseous fuels or combustibles, such as hydro-carbon oils or gases or the like, and 15 particularly to that class of burners designed, organized and adapted for utilizing a mixture such as oil and steam or the like.

The invention has for its object to provide an improved burner of the general character above stated which will be superior 20 in point of cleanliness of operation, freedom from smut and smoke production, completeness of combustion, economy of fuel units, high percentage of heat unit production, and 25 facility of control, all combined with simplicity and inexpensiveness of construction and organization; and which will be generally superior in efficiency and serviceability, as well as adaptability to a wide range of use 30 and service.

We are well aware that various burners have been devised and adapted for the mixture of various elements with the fuel prior to the combustion of the same; but it has 35 been a particular object of our experimentation, to which object we have attained as evidenced by extended periods of successful practice of the invention, to provide a burner which would cause or control combustion of 40 the fuel with materially increased resultant heat values, and materially decreased or substantially obviated production of smoke and smut, to the end that an intense and highly caloric, as well as brilliant and clean flame, 45 may be produced, with all the attendant advantages and factors of increased efficiency.

According to the invention, we provide a burner having suitable supply means for the fuel and other ingredients or constituents, as, for instance, for steam and mineral oil. These ingredients are mixed 50 in an elongated chamber which surrounds a steam chamber, and the ingredients are thoroughly mixed and heated when they arrive at the operative end of the burner which is provided with a bifurcated portion the

members of which are slotted for the projection of the heated and mixed ingredients. Between these members of the burner end portion is disposed a steam duct or burner tip which constitutes the terminal portion 60 of the steam chamber within the mixing chamber, and from which steam is ejected so as to commingle with the mixed steam and oil jets ejected by the burner members, 65 which are provided with slotted tips, causing fusion of the two jets of mixed or combined ingredients; all three jets merging at a common point beyond the termini of the burner tips, at which point combustion is 70 supported.

The highly combustible gases generated by the mixed steam and oil under the violent merging of the three jets, support combustion accompanied by a brilliant flame which 75 is approximately free from smoke and smut.

We have found that a burner organized and constructed in accordance with the above general provision, inter-relation and construction of parts, members and features, is 80 of the highest efficiency and is accompanied in operation by marked fuel economy, when the heat units developed are taken into consideration.

The invention consists in the novel and 85 useful provision, construction, organization, combination, association, inter-relation and general arrangement of parts, members and features, all as hereinafter described, shown in the drawings, and finally pointed out in 90 claims.

In the drawings, Figure 1 is a top plan view, partly in section and partly broken away for clearness of illustration, of a burner constructed and organized in accordance with the invention; Fig. 2 is a front end elevation of the burner; and, Fig. 3 is a vertical longitudinal sectional view, partly in section and partly broken away for clearness of illustration, of the burner illustrated 95 in the other figures, and more fully disclosing the general organization and construction and inter-relation of the parts and features thereof. This view is taken upon the line 3—3, Fig. 1.

Corresponding parts in all the figures are denoted by the same reference characters.

Referring with particularity to the drawings, A designates a burner organized in accordance with the invention and provided 110 with oil supply means B and steam supply means C. In the main, the burner A com-

prises three tubular and substantially or preferably concentric members *a*, *b* and *c*, the same being recited in the order of their arrangement in enumeration inwardly toward the common center. The members *a* and *c* are substantially co-extensive longitudinally, being joined to constitute a burner tip portion *d* which comprises in turn three members *f*, *g* and *h*. The member *b* is relatively shorter than the tubular members *a* and *c*, terminating inwardly of the burner tip portion *d*. An annular chamber *p* separates the tubular members *b* and *a*, an annular chamber *k* separates the tubular members *b* and *c*, and an annular chamber *m* separates the tubular members *a* and *c* outwardly of the tubular member *b*, said chamber *m* communicating with the chambers *p* and *k*. The tubular member *b* has a threaded connection with the inner end of the tubular member *a*, as at 4, and the tubular member *c* has a threaded connection with the inner end of the tubular member *b*, as at 5, and likewise has a threaded connection 25 with the outer end of the tubular member *a*, as at 6, intermediate of the members *f* and *g* and concentric with and communicating with the member *h*; the members *f* and *g* and *h* of the burner tip portion *d* being preferably extensions of the tubular formation of the member *a*, which is enlarged to form said burner tip portion. The members *f* and *g* directly communicate with the chamber *m*, and the member *h* communicates only 35 with the interior of the tubular member *c*. The burner tip portion members *f* and *g* are each substantially of the same diameter as the tubular member *a*, or of slightly less diameter, and project oppositely in opposite 40 curved formations, terminating in slotted tips 7 and 8 respectively which are directed toward each other each at an angle of substantially 15 degrees with relation to the longitudinal axis of the tubular member *c* 45 and of the burner tip portion member *h*; which latter is disposed equi-distant from the members *f* and *g* and is provided with a slotted tip 9 intermediate of the tips 7 and 8; the relative arrangement and disposition 50 of the tips 7, 8 and 9 being such that the jets proceeding therefrom will merge at a common point outward of all of the three tips, and the forces of all three jets will be united at that point, which will be the point 55 at which combustion is supported. The slits in the several tips are elongated or relatively narrow, as clearly shown in Fig. 2. An oil supply pipe 10 is connected with the tubular member *a* at the inner end and laterally of the same, and may include a union joint 11 for purposes of assemblage and disconnection. The pipe 10 is also supplied with a valve casing 12 containing any suitable type of valve having a stem 13 and hand wheel 14 to control the supply of oil. 60

The oil supply means B are thus constituted. The steam supply means C may comprise a main steam supply pipe 15 connected by unions 16 and 17 respectively with branch steam supply pipes 18 and 19 respectively, 70 which are respectively provided with valve casings 20 and 21; and the branch steam supply pipes 18 and 19 may include unions 22 and 23 respectively for purposes of assemblage and disconnection. The valve casings 20 and 21 include suitable valves controlling the pipes 18 and 19, such valves being provided with stems and hand wheels, a stem 24 and hand wheel 25 for the valve in the casing 20, and a stem 26 and hand wheel 27 for the valve in the casing 21. By manipulating the hand wheels 14, 25 and 27 the supply of oil in the first instance, and of steam in each latter instance, may be effectively controlled. The pipe 19 communicates with the tubular member *b* at the inner end and laterally thereof, and the pipe 18 communicates with the tubular member *c* at the inner end thereof. A union 28 may be provided for connecting the pipe 18 with the tubular member *c*; and the several unions shown and described are of elbow, ring or other formation as best serves the purpose of each. 90

It will be noted that the pipe 18 serves 95 with steam the tubular member *c* leading directly to the tip 9; that the pipe 10 serves with oil the tubular member *a*, through the annular chamber *p*, then the annular chamber *m* leading directly to the tips 7 and 8; 100 and that the pipe 19 serves with steam the tubular member *b* and the annular chamber *k* as well as the tubular member *a* and the annular chamber *m* leading directly to the tips 7 and 8. The steam issuing from the 105 outer end of the annular chamber *k* mixes with the oil in the annular chamber *m*, surrounding the tubular member *c* which is heated by the steam within the same; and the mixture of steam and oil within the annular chamber *m*, under such thermal influence, passes to the burner tip portion *d*, such annular chamber *m* serving as a mixing chamber for the oil and steam which become intimately mixed within the burner 110 tip portion *d*. 115

The resultant mixture is projected under pressure from the relatively narrow or elongated slits in the tips 7 and 8, and steam issues from the tip 9 of the same formation 120 under expansive pressure. The convergence of the paths of projection of the mixed oil and steam jets and of the intermediate steam jet, due to the relative disposition of the tips 7, 8 and 9, causes the three jets or 125 streams, to merge intimately, and a production of highly and freely combustible mixture ensues, and the spray from the steam tip 9 causes a complete merger or fusion of the mixed oil and steam streams from the tips 7, 130

and 8, the resultant mixture supporting perfect combustion of high thermal intensity, free from smoke or smut. It will be noted that the mixing or commingling of the oil and steam in the annular mixing chamber *m*, forward of the annular chamber *k*, is influenced by the heat radiated from the tubular member *c* which extends centrally through said mixing chamber, so that the oil and steam are thoroughly mixed when the mixture arrives at the burner tip portion *d*; and the mixture of steam and oil, then traverses the members *f* and *g* of the burner tip portion and is emitted from the tips 7 and 8 thereof simultaneously with the emission of steam from the tip 9 of the burner tip portion member *h*.

The supply of oil to the mixing chamber *m*, and of steam to the mixing chamber *m*, through the annular chambers *p* and *k* respectively, may be regulated by the valves within the casings 12 and 21 respectively; and the supply of steam to the tubular member *c* may be regulated by the valve within the casing 20; so that the relative proportion of oil and of steam for the mixture, and of steam for the steam jet issuing from the tip 9, may at all times be determined, and so that the best working conditions may be determined and maintained, in accordance with the nature of surface to which the burner as an entirety is to be subjected.

It is manifest that we may depart in many respects from the specific showing in the drawings and the description in the specification, in practising our invention and carrying the same into operation and effect; and we do not desire to be understood as limiting ourselves to the particular construction, form, combination and inter-relation of parts, members and features as shown and described, but reserve the right to vary the same, in adapting the invention to varying conditions of use and service, without departing from the spirit of the invention and the terms of the following claims.

Having thus described our invention, we claim and desire to secure by Letters Patent:—

50 1. A burner comprising a mixing chamber, means for supplying oil to the mixing chamber, means for supplying an atomizing fluid to the mixing chamber, spaced tips applied to the mixing chamber and arranged to produce intersecting jets of the mixture from the mixing chamber, an intermediate tip arranged to provide a third intersecting jet, and an atomizing fluid supply pipe communicating with the intermediate tip.

60 2. A burner comprising a mixing chamber, a first tubular member extending within and sealed from the mixing chamber, a second tubular member within and opening at one end within the mixing chamber, means for supplying one fluid component to the

mixing chamber, means for supplying another fluid component to the mixing chamber through said second tubular member, and means for supplying the latter fluid component to said first tubular member; spaced tips communicating with said mixing chamber; and an intermediate tip communicating with said first tubular member. 70

3. A burner comprising a mixing chamber, a first tubular member extending within and sealed from the mixing chamber, a second tubular member within and opening at one end within the mixing chamber, means for supplying one fluid component to the mixing chamber, means for supplying another fluid component to the mixing chamber through said second tubular member, and means for supplying the latter fluid component to said first tubular member; spaced tips communicating with said mixing chamber; and an intermediate tip communicating with said first tubular member; said spaced tips being arranged to direct streams convergently. 80

4. A burner comprising a mixing chamber, a first tubular member extending within and sealed from the mixing chamber, a second tubular member within and opening at one end within the mixing chamber, means for supplying one fluid component to the mixing chamber, means for supplying another fluid component to the mixing chamber through said second tubular member, and means for supplying the latter fluid component to said first tubular member; spaced tips communicating with said mixing chamber; and an intermediate tip communicating with said first tubular member; said spaced tips being arranged to direct streams convergently, and said intermediate tip being arranged to direct a stream to the point of convergence of the streams from said spaced tips. 95

5. A burner comprising a mixing chamber, a steam chamber arranged within and sealed from the mixing chamber, means for supplying oil to the mixing chamber, means for supplying steam to the mixing chamber, spaced tips mounted upon the mixing chamber and producing intersecting jets of the mixture from the mixing chamber, and a third tip communicating with the steam chamber and producing a third intersecting jet. 110

6. A burner comprising a mixing chamber, a steam chamber arranged within and sealed from the mixing chamber, means for supplying oil to the mixing chamber, a tubular member partially surrounding the steam chamber and communicating with the mixing chamber, means for supplying steam to the said tubular member to be mixed with the oil, spaced tips applied to the mixing chamber and arranged to produce intersecting jets of the mixture, and a third tip ap- 115 120 125 130

plied to the steam chamber and also producing an intersecting jet.

7. A burner comprising a mixing chamber having a head at one end thereof, a steam chamber arranged within the mixing chamber and sealed therefrom, oil supply means for the mixing chamber, a tubular member partially surrounding the steam chamber and communicating with the mixing chamber, steam supply means communicating with the steam chamber and tubular member, a pair of tips applied to the head of the mixing chamber and arranged to produce intersecting jets of the mixture, and a third

tip in communication with the steam chamber and also producing an intersecting jet. 15

In testimony whereof, we have signed our names to this specification in the presence of two subscribing witnesses.
